US00D790581S

(12) **United States Design Patent** (10) **Patent No.:** **US D790,581 S**
Chaudhri et al. (45) **Date of Patent:** **** Jun. 27, 2017**

(54) **DISPLAY SCREEN OR PORTION THEREOF
WITH GRAPHICAL USER INTERFACE**

6,014,142 A 1/2000 LaHood
6,061,457 A 5/2000 Stockhamer
D462,076 S 8/2002 Robbin et al.
D472,244 S 3/2003 Wasko
6,556,222 B1 4/2003 Narayanaswami

(71) Applicant: **Apple Inc.**, Cupertino, CA (US)

(Continued)

(72) Inventors: **Imran Chaudhri**, San Francisco, CA (US); **Jonathan P. Ive**, San Francisco, CA (US)

FOREIGN PATENT DOCUMENTS

(73) Assignee: **Apple Inc.**, Cupertino, CA (US)

EM 000584529-0003 11/2006
EM 00135393-0005 2/2013

(Continued)

(**) Term: **15 Years**

(21) Appl. No.: **29/574,393**

(22) Filed: **Aug. 15, 2016**

Related U.S. Application Data

(63) Continuation of application No. 29/538,627, filed on Sep. 4, 2015, now Pat. No. Des. 763,895, which is a continuation of application No. 29/457,342, filed on Jun. 9, 2013, now Pat. No. Des. 738,905.

OTHER PUBLICATIONS

No need to make exercise playlists with these music apps, announced Jun. 27, 2015 [online]. [site visited Apr. 12, 2017]. Available from Internet, URL: <<http://www.digitaltrends.com/health-fitness/best-exercise-music-app/>>.*

CLAIM

U.S. PATENT DOCUMENTS

D277,109 S 1/1985 Gordon
5,966,126 A 10/1999 Szabo
5,995,093 A 11/1999 Lamboume et al.

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.
